UNITED STATES PATENT OFFICE

EINAR JANSEN, OF CHICAGO, ILLINOIS, ASSIGNOR OF ONE-HALF TO MARTIN S. HAMM,
OF CHICAGO, ILLINOIS

TOY TELEPHONE

Application filed May 2, 1931. Serial No. 534,566.

This invention relates to a toy simulating in appearance a conventional telephone instrument and having a casing formed to house a phonograph unit. The main object of this invention is to provide an improved toy telephone construction in which the audible sound produced by the phonograph in the casing is transmitted through a conduit directly to the telephone receiver. Another object is to provide an improved toy telephone of this character in which the phonograph reproducing element is automatically moved into and out of engagement with a phonograph record in response to removal and replacement respectively of the receiver element on its supporting bracket. A further object is to provide an improved toy telephone construction in which the reproducer element is automatically shifted to starting position upon replacement of the receiver element on its supporting bracket. And a still further object is to produce a toy telephone of the character mentioned having means which simulates the dialing mechanism of the conventional type of telephone instrument arranged for winding the phonograph motor. The invention consists in certain features and elements of construction in combination, herein shown and described, as indicated by the claims.

In the drawings:

Figure 1 is a plan view of a toy telephone instrument embodying the present invention.

Figure 2 is a view in side elevation.

Figure 3 is a view in side elevation with the receiver removed and with parts in section to show details of construction.

Figure 4 is a transverse sectional view taken substantially as indicated at line, 4-4, on Figure 3.

Figure 5 is a horizontal transverse section through the lower portion of the casing looking down upon the driving mechanism, and taken substantially as indicated at line, 5-5, on Figure 6.

Figure 6 is a vertical section through the casing showing the mechanism in elevation, with the reproducer in engagement with the phonograph record.

Figure 7 is a more or less diagrammatic

view showing part of the mechanism for controlling the movement of the reproducer.

For the purpose of illustration the present invention is shown embodied in a form simulating a "cradle" type of conventional telephone instrument, and includes a casing, 10, composed of two parts, the lower part indicated at 10^a, which is of substantially cylindrical form and serves to completely house the driving mechanism, as seen in Fig. 6, and an upper casing part, 10^b, which is adapted to telescopically engage with the lower casing part, 10^a. The upper casing portion is formed with a horizontally extending shelf, 10^c, which merges into an upwardly extending casing portion which is in the form of a frustrated cone flattened at one side and closed at its upper end by a top, 10^d. The extreme upper end of this frustrated cone portion of the casing is substantially cylindrical and is adapted to have telescopically associated therewith an annular, skirted member, 12, which is rigidly secured to a movable bracket, 13, formed to provide a seat for a combined receiver and transmitter indicated at 15. For the purposes of the present invention, the transmitter indicated at 15^b, need not be an operative mechanism but merely a dummy to carry out the resemblance of the toy to a working telephone.

Mounted in the completely enclosed lower casing portion, 10^a, is a spring motor indicated generally at 17, which is adapted to impart rotation to a driving gear, 18, which in turn meshes with a pinion, 19, carried on a vertical intermediate shaft, 20, journaled in the top and bottom walls, 10^e, and 10^f, of said lower casing part; and rigidly mounted on said intermediate shaft, above the pinion is a gear, 22, meshing with a pinion, 23, on the turn-table driving shaft, 24, which is also journaled in the top and bottom walls, 10^e and 10^f, of said lower casing part. Said turn-table shaft projects upwardly through the top, 10^e, of the casing, and has rigidly mounted on said extension a turn-table, 25, for carrying a phonograph record indicated at 26.

The speed of rotation of the turn-table is controlled by a conventional type of centrifugal governor, as seen in Figure 5, which

includes a shaft, 52, journaled at its ends in the wall of the lower casing part, 10^a. This shaft is formed with a worm, 53, operatively meshed with a gear, 54, which is rigidly secured on the turn-table shaft, 24, just above the drive pinion, 23. The governor proper includes a plurality of flexible members, 55, such as springs arranged about the shaft, 52, and which are rigidly connected to said shaft 5 at one end by the member, 56, and their other ends being connected to a floating friction disk, 57. Secured about midway of the length of said members, 55, are counter-weights, 58, which by the centrifugal force 10 set up by rotation of the shaft, 52, cause said members, 55, to bow outwardly, thereby moving the friction disk, 57, axially along the shaft. An adjustment lever, 59, which is bell crank in form, is pivoted at 60, to the 15 bottom of the casing, and has one arm projecting through the wall of the casing to permit manual shifting of the lever to a desired position; the other arm, 59^a, of said lever extends adjacent the friction disk and carries 20 at its extreme end a block of friction material, 61, such as felt, for encounter with the disk, 57, which serves to limit the axial movement of said disk and control the speed of 25 rotation of the turn-table, 25. It will be manifest that by shifting the lever, 59, so as to vary the permissible amount of axial movement of the friction disk, 57, correspondingly varies the speed of rotation of 30 the turn-table.

25 The means for winding the spring motor, 17, simulates the conventional type of dialing mechanism employed on modern telephone instruments and includes a disk, 29, fixedly secured on the horizontal portion, 10^c, of the 35 upper casing part and a vertically spaced rotatable disk, 30, mounted on and rotatable with a shaft, 31, the lower end of which extends through the horizontal portion, 10^c, of the casing, and is detachably engageable with 40 the upper end of the shaft, 17^a, of the spring motor, 17. It will be manifest that the detachable connection between the adjacent ends of shafts, 17^a and 31, permits separation of the upper and lower portions of the 45 casing, affording access to the turn-table, 25, to permit removal and replacement of phonograph records thereon. The disk, 30, is provided with a plurality of concentrically arranged apertures indicated at 32 for engagement by the finger so that the disk, 30, 50 may be rotated in clockwise direction only for winding up the spring motor. The fixed disk, 29, is provided at its outer periphery with an upstanding lug with a curved projection indicated at 33 overlying the upper 55 surface of the disk, 30, and is adapted to serve as a stop for limiting the amount of rotation of the disk, 30, by engagement of the finger in one of the apertures, 32. The lower disk, 60 65 29, is preferably provided on its upper sur-

face with numerals or letters registering with the apertures, 32, in the disk, 30, to simulate the conventional type of dialing mechanism, and preferably these numerals are so located that there will be a number of apertures intermediate the aperture which is in registration with the first number or letter and the stop, 33. Thus the user will be led to engage one of the apertures over one of the numerals and swing the disk until the finger encounters the stop, 33, insuring that the disk, 31, will at least be rotated a substantial amount for winding up the spring motor sufficiently for playing of a complete record.

Disposed in the upwardly extending cone portion of the casing part is a reproducing element, 36, whose lower end is provided with a stylus, 37, adapted to engage the phonograph record, 26. The upper end of the reproducer is formed with an eye which is slidably supported on an arm, 39, of a bell crank member which is pivoted at 40 to the wall of the casing and whose other arm, 41, extends in a downward direction and is provided with a pad, 41^a, of friction material adapted to engage the outer peripheral edge of the turn-table, 25, for stopping it. It is desirable to provide means whereby the reproducer element, 36, may be automatically moved into and out of engagement with the phonograph record in response to the removal or the replacement of the receiver element on its supporting bracket, and for this purpose I show a rod, 43, rigidly secured at its upper end to the supporting bracket, 13, with its lower end extending through the top portion, 10^d, of the upper casing part and pivotally connected to a lever, 44, which is pivotally mounted on a transversely extending rod, 45, fixedly secured at its opposite ends in the wall of the casing, as seen in Figure 4. The opposite end of said lever, 44, provides a loose pivotal connection with the outer end of the bell crank arm, 39. A coil spring, 46, is interposed between the under side of the bracket, 13, and the top portion, 10^d, of the casing surrounding said rod, 43, and normally urges the bracket, 13, in upward direction as seen in Figure 3.

It is to be understood that when the receiver, 15, is placed on the supporting bracket, 13, its weight is sufficient to overcome the spring, 46, and the downward movement of the rod, 43, swings the lever, 44, about its pivot rod, 45, which in turn swings the bell crank arm, 39, in an upward direction to substantially the position seen in Figure 7, and simultaneously the arm, 41, of the bell crank is moved into braking engagement with the turn-table, 25, for stopping it. This movement of the bell crank about its pivot, 40, raises the reproducer, 36, out of engagement with the record, 26, and because of the inclination of the arm, 39, in this position, the reproducer will be caused to slide outwardly along said arm toward the pivot, 40, to the

position indicated in full lines in Figure 7 with its stylus supported just out of contact with the record. Then when the receiver, 15, is removed from its supporting bracket, 13, the spring, 46, urges said bracket upwardly and the upward movement of the rod, 43, rocks the lever, 44, which in turn swings the bell crank about its pivot so as to shift the arm, 39, to a substantially horizontal position, moving the brake arm, 41, of the bell crank out of contact with the turn-table to permit the latter to be set in motion under control of its spring motor, 17. At the same time the stylus, 37, is lowered into contact with the record. In this position the arm, 39, of the bell crank serves to guide the reproducer element, 36, as it traverses the record, 26, permitting it to follow the record groove during the playing operation and also insuring return of the reproducer, 36, to starting position when the arm, 39, is tilted away from the horizontal.

The casing of the reproducer is formed to confine the sounds produced thereby, and is provided with a sound chamber, 36^a, to the end of which is connected a flexible conduit, 50, which extends through an aperture formed in the wall of the upper casing part, 10^b, and has its upper end connected into the combined receiver and transmitter unit, 15, entering, for convenience, at the transmitter end, 15^c, and extending therein for connection to the conduit, 15^c, of the receiver, 15^a, thus providing a conduit for transmission of the sounds produced by the phonograph reproducer directly to the receiver. This feature, taken together with the automatic control of the reproducer, results in a novel and interesting combination, since the sounds may be heard through the receiver, 15^a, almost instantaneously upon its removal from its supporting bracket, 13, and when the sound is no longer heard through the receiver it may be replaced on its bracket and will automatically stop the phonograph. Forming the casing in two parts as above described permits convenient separation thereof to afford access to the phonograph turn-table for reversing or replacing the phonograph records.

It will be manifest that the construction herein described may also be used in recording sound for producing a phonograph record. This may be done by providing the proper type of stylus and record disk, and by delivering the sound through the received portion, 15^a, of the unit, 15.

Although I have shown and described a preferred embodiment of my invention, it is manifest that the proportion and arrangement of parts may be varied without departing from the spirit and scope thereof. I do not, therefore, wish to be understood as limiting myself to the particular construction

herein shown and described, except as indicated in the appended claims.

I claim:

1. A toy of the class described, including a hollow casing having a movable supporting bracket, a receiver element adapted to be carried by said bracket, a motor driven phonograph in said casing including a record-carrying turntable and a reproducing element, together with means connected to the reproducer and associated with the bracket and responsive to the movement thereof when said receiver is replaced thereon, for raising said reproducer out of engagement with the record.

2. A toy of the class described, including a hollow casing having a movable supporting bracket, a receiver element adapted to be carried by said bracket, a motor driven phonograph in said casing including a record-carrying turntable and a reproducing element, together with means connected to the reproducer and associated with the bracket and responsive to the movement thereof when said receiver is replaced thereon, for raising said reproducer out of engagement with the record, said means being adapted to automatically lower the reproducer into engagement with its record when said bracket is released by the removal of the receiver therefrom.

3. In the construction defined in claim 2, said means including a spring urging the bracket in the direction for moving the reproducer into engagement with the record.

4. A toy of the class described, including a hollow casing having a movable supporting bracket, a receiver element adapted to be carried by said bracket, a motor driven phonograph in said casing including a record-carrying turntable and a reproducing element, and means connected to the reproducer and associated with the bracket and responsive to the movement thereof when the receiver is replaced thereon for raising said reproducer out of engagement with the record, said means being arranged for causing shifting of the reproducer to starting position adjacent the outer edge of the record, incident to such raising movement.

5. In the construction defined in claim 4, spring means for opposing movement of the reproducer out of engagement with the record.

6. A toy of the class described, including a hollow casing having a movable supporting bracket, a receiver element adapted to be carried by said bracket, a motor driven phonograph in said casing including a record-carrying turntable and a reproducing element, and means connected to the reproducer and actuated by the bracket when the receiver is replaced thereon for raising the reproducer out of engagement with the record, and adapted when said receiver is removed from

its bracket to automatically lower said reproducer into engagement with the record, said means being arranged for causing shifting of the reproducer to starting position adjacent the outer edge of the record, when said reproducer is raised out of engagement with the record.

7. In the construction defined in claim 6, said means including an arm on which the reproducer is slidably supported, and adapted to assume a substantially horizontal position, when the reproducer has been lowered into engagement with the record, for guiding said reproducer as it traverses the record.

10 8. In the construction defined in claim 6, said means including an arm on which the reproducer is slidably supported, said arm being pivoted at one end, and being adapted to assume an inclined position when the bracket is released by the removal of the receiver, for causing said reproducer to slide 20 downwardly along said arm to starting position.

15 9. In the construction defined in claim 6, said means comprising a bell crank lever pivoted in said casing and having one arm engageable as a brake with said turntable, the other arm normally extending over the turn-table for supporting the reproducer, 30 said arm being caused to swing upwardly when the bracket is moved incident to the replacement of the receiver thereon, thereby raising the reproducer out of contact with the record and causing it to slide outwardly 35 along the inclined arm toward the pivot, adjacent the outer edge of the record, such movement of the supporting arm of the bell crank simultaneously moving the other arm into braking relation with the turntable.

40 10. In the construction defined in claim 6, said means comprising a bell crank lever pivoted in said casing and having one arm engageable as a brake with said turntable, the other arm normally extending over the turn-table for supporting the reproducer, said 45 arm being caused to swing upwardly when the bracket is moved incident to the replacement of the receiver thereon, thereby raising the reproducer out of contact with the record 50 and causing it to slide outwardly along the inclined arm toward the pivot, adjacent the outer edge of the record, such movement of the supporting arm of the bell crank simultaneously moving the other arm into braking 55 relation with the turntable, said bell crank being adapted in response to movement of the bracket when the receiver is removed to swing the brake arm of the bell crank out of engagement with the turntable, and dispose 60 its other arm in substantially horizontal position, with the reproducer engaging the record.

11. In the construction defined in claim 6, said means including linkage and a spring element acting to urge the reproducer into 65 engagement with the record when the bracket

has been permitted to move by removal of the receiver therefrom.

12. A toy of the class described, including a hollow casing having a movable supporting bracket, a receiver element adapted to be carried by said bracket, a motor driven phonograph in said casing including a record-carrying turntable and a reproducer element, means connected to the reproducer and associated with the bracket and responsive to the movement thereof when the receiver is replaced thereon for raising the reproducer out of engagement with the record, said means being arranged to automatically lower the reproducer into operative engagement with the record when the bracket is released by the removal of the receiver therefrom, and a flexible conduit connecting the receiver and reproducer for transmitting the sound to said receiver.

13. In a toy telephone, a hollow casing, a motor driven phonograph in said casing including a record-carrying turntable, a spring motor operatively connected to the turntable, and a reproducing element, and exteriorly accessible means for winding the spring motor, consisting of a disk provided with a plurality of concentric apertures for receiving the fingers in rotating it, and simulating a dialing mechanism of a conventional telephone, said disk having an operative connection with the spring motor.

14. In the construction defined in claim 13, said hollow casing being composed of two main portions detachably connected, to permit access to the phonograph records; the upper part having a flat recess for accomodating the winding disk.

15. In the construction defined in claim 13, said hollow casing being composed of two main portions detachably connected, to permit access to the phonograph records; the upper part having a flat recess for accomodating the winding disk, and said winding disk having a detachable drive connection 110 with said spring motor.

In testimony whereof, I have hereunto set my hand at Chicago, Illinois, this 30th day of April, 1931.

EINAR JANSEN. 115
